(57) **CLAIM**

I claim the ornamental design for a boot key apparatus, substantially as shown and described.

DESCRIPTION

FIG. 1 shows a front, top, and right side perspective view of the boot key apparatus according to one embodiment of the invention.

FIG. 2 shows a front elevational view thereof.

FIG. 3 shows a top plan view thereof, the bottom plan view being a mirror image; and,

FIG. 4 shows a left side elevational view thereof, the right side elevational view being a mirror image; and,

FIG. 5 shows a rear elevational view thereof.

1 Claim, 2 Drawing Sheets

FIG. 1

FIG. 2

FIG. 3

FIG. 4

FIG. 5
